UNITED STATES PATENT OFFICE

146,530

DESIGN FOR A PICTURE STAND

Joseph J. Swartzmiller, Carnegie, Pa.

Application May 3, 1946, Serial No. 129,288

Term of patent 3½ years

(Cl. D29—20)

To all whom it may concern:

Be it known that I, Joseph J. Swartzmiller, a citizen of the United States, residing in Carnegie, in the county of Allegheny and State of Pennsylvania, have invented a new, original, and ornamental Design for a Picture Stand, of which the following is a specification, reference being had to the accompanying drawing, forming part thereof.

I claim:

The ornamental design for a picture stand, as shown.

JOSEPH J. SWARTZMILLER.
